UNITED STATES PATENT OFFICE

ELTON C. METCALF, OF WRENTHAM, MASSACHUSETTS, ASSIGNOR TO MURDOCK & GEB COMPANY, OF FRANKLIN, MASSACHUSETTS

BOBBIN HOLDER

Application filed September 10, 1930. Serial No. 480,914.

This invention relates to certain new and useful improvements in bobbin holders and the primary object thereof, is to improve the means for pivotally mounting the jaws, whereby to cause the bobbin to be accurately held and to run true, without requiring accurate placement of the bobbin on the holder.

A further object of the invention is to provide a holder which is readily adaptable for use with bobbins of varying sizes and further to provide means of the character just mentioned which acts to securely maintain the clamping member for the jaws in position, and to also prevent excessive inward strain such as might effect injury to the clamping member.

In the drawings;

Figure 1 is a side elevation of the invention;

Figure 2 is a top plan view;

Figure 3 is a section on line 3—3 of Figure 1.

Figure 4 is a section on line 4—4 of Figure 1.

Figure 5 is a view similar to Figure 3 of a modified form of the invention and

Figure 6 is a top plan view of Figure 5.

In proceeding in accordance with the present invention a base member 1 is provided which is of substantially cup-shape and which is provided with an opening 2 in the center of its bottom. Three bobbin engaging jaws 3 are employed, each being of substantially L or right angular form and having the free end portions of the jaws curved at 4 to

provide a seat for a coil spring 5, the latter being of circular form and acting to move the convex faces 6 of the jaws against the bobbin (not shown). The lower ends of the jaws 3 are provided with outwardly extending pintles or lugs 6, which lugs are disposed on the opposite sides of the feet 7 of the jaws. For the purpose of pivotally mounting each of the three jaws a fulcrum member 8 is pro-

vided, the member being formed with a triangular arrangement of pairs of sockets or bearings 9 in which the lugs or pintles 6 engage. The fulcrum member 8 is further provided with arms 10 that project outwardly of the sockets or bearings 9 and which engage

the opposite sides of the feet of the jaws so as to prevent the jaws from having other than a pivotal movement. The side arms 10 of the member 8 are provided with upward projections 11 to engage a flat washer 12, which latter seats upon the member 8 and engages the feet 7 of the jaws as shown particularly in Figure 3. A cup member 13 seats upon the washer 12 and has its rim turned outwardly at 14 to provide an abutment which restricts inward pivotal movement of the jaws under the tension of the spring 5. For the purpose of securely relating the parts as above described, a hollow rivet 15 is provided which has a shoulder 16 against which the bottom of the base member 1 abuts and which has its free upper end 17 spun or flanged outwardly so as to tightly clamp the parts 13, 12, and 8, against the circular shoulder 16. It will be understood that the usual spindle is received through the hollow interior of the rivet 15.

With the form of cup member described in connection with Figures 1 to 4 it will be seen that bobbins of varying diameters can be accommodated due to the plane upper face of the cup 13.

In Figures 5 and 6 a modified form of the invention is disclosed and wherein the parts corresponding to those described in connection with the preferred form of the invention in Figures 1 and 2, 3 and 4 are provided with prime marks, these parts being of identical construction to the corresponding parts of Figures 1 to 4. The only difference resides in that of the cup member 13', which latter is provided with an outwardly struck circular bead 17 which bead as shown in Figure 5 of the drawings is of concavo-convex cross section. In this form of the invention same is adapted to bobbins of a definite or predetermined size which latter are engaged by the circular bead 17 and held in position thereby.

In all the forms of the invention it will be seen that the parts are brought into close relation providing a very compact arrangement and one in which all of the parts can be connected by a rivet of very short length, thus providing a structure which not only occupies

a minimum of space, but also one wherein the parts, due to their close relation mutually brace and strengthen one another. It will further be noted that the feet of the jaws are completely housed within the base member and are accordingly protected thereby.

Having thus described my invention what I claim as new and desire to secure by Letters Patent is:—

- 10 1. In a bobbin holder, a base member of substantially cup-shape substantially L-shaped jaws having their feet disposed within the base member and provided on their sides with oppositely extending pintles, a fulcrum member common to all of the jaws having socket portions to receive the pintles of the respective jaws and having arms which extend along the sides of the jaws, the arms being provided with upwardly extending projections, and acting to hold the jaws against other than pivotal movement, a washer seated on the upper face of the fulcrum member and overlying the feet of the jaws to prevent upward movement of the jaws out of the base member, a circular coil spring engaged about the outer ends of the jaws to tension same, a bobbin supporting member of substantially cup shape superimposed upon said washer, and a hollow rivet extending through the base member, the fulcrum member, the washer, and the bobbin supporting member and being headed into engagement therewith to rigidly connect said parts.

35 2. In a bobbin holder, a base member of substantially cup shape, substantially L-shaped jaws having their feet disposed within the base member and provided on their sides with oppositely extending pintles, a fulcrum member common to all of the jaws having socket portions to receive the pintles of the respective jaws and having arms which extend along the sides of the jaws, and the arms being provided with upwardly extending projections, and acting to hold the jaws against other than pivotal movement, a washer seated on the upper face of the fulcrum member and overlying the feet of the jaws to prevent upward movement of the jaws out of the base member, a circular coil spring engaged about the outer ends of the jaws to tension same, a bobbin supporting member of substantially cup shape superimposed upon said washer, and a hollow rivet extending through the base member, the fulcrum member, the washer, and the bobbin supporting member and being headed into engagement therewith to rigidly connect said parts, the rim of the cup like bobbin supporting member having its free edge turned outwardly to engage the jaws and to restrict inward movement thereof under the tension of the spring.

60 3. In a bobbin holder, a base member of substantially cup-shape, substantially L-

shaped jaws having their feet disposed within the base member and provided on their sides with oppositely extending pintles a fulcrum member common to all of the jaws having socket portions to receive the pintles of the respective jaws and having arms which extend along the sides of the jaws, the arms being provided with upwardly extending projections, and acting to hold the jaws against other than pivotal movement, a washer seated on the upper face of the fulcrum member and overlying the feet of the jaws to prevent upward movement of the jaws out of the base member, a circular coil spring engaged about the outer ends of the jaws to tension same, a bobbin supporting member of substantially cup shape superimposed upon said washer, said cup-like member having its rim formed to engage the jaws to restrict inward movement thereof under tension of the spring, and the bottom of the cup like bobbin supporting member being formed with an intermediate circular bead to engage the bobbin, and a hollow rivet extending through the base member, the fulcrum member, the washer, and the bobbin supporting member and being headed into engagement therewith to rigidly connect said parts.

4. In combination with a base member, a series of jaws having feet disposed on the base member and provided with pintles, fulcrum means common to all of the jaws and having portions to receive the pintles whereby to pivotally mount the jaws, a member engaged over said fulcrum means and extending over the jaws to prevent outward movement thereof relative to the base member, a bobbin supporting member seated on said first named member, and means to rigidly connect the base member, the fulcrum means, the second named member and the bobbin supporting member. 105

In testimony whereof I have hereunto signed my name. 110
